Primary Examiner — Thomas Johannes(74) *Attorney, Agent, or Firm* — Jonathan Spangler; Rory Schermerhorn**CLAIM**

The ornamental design for an electrode connector, substantially as shown and described.

DESCRIPTION

FIG. 1 is a perspective view of an electrode connector showing our new design, in a typical usage environment; and, FIG. 2 is another perspective view thereof, shown in isolation from a usage environment.

Those portions of the electrode connector shown in broken lines show unclaimed subject matter only and form no part of the claimed design.
